TURNTABLE

Application filed March 14, 1929. Serial No. 346,946.

This invention relates generally to turntables for use in garages, or vehicle service stations, for supporting motor vehicles, and has particular reference to a superstructure 5 for use with an hydraulic or pneumatic elevator, although obviously the superstructure may be used as a part of an ordinary turntable.

One object of the present invention is the provision of a device of the above mentioned character which is formed, in part, of a reinforced pressing.

Another object of the invention is the provision of a superstructure for motor-vehicle lifts which includes a pressed metal head adapted to be supported by the upper end of a piston of an hydraulic or pneumatic lift.

A further object of the invention is the provision of a superstructure for a vehicle lift which includes spaced rails secured to and supported by a pressed metal head, a portion of which latter is formed to provide a center bearing.

Still another object of the invention is the provision of means permanently secured to the upper end of a ram of an hydraulic or pneumatic lift for supporting a superstructure formed of a single pressing.

A further object of the invention is the provision of a turntable for motor vehicles which is simple to manufacture and strong and durable in operation.

Other objects and advantages of this invention will be apparent from the following description taken in conjunction with the accompanying drawings in which:

Figure 1 is a sectional view of the superstructure shown as mounted on the upper end of the ram of an hydraulic lift;

Fig. 2 is a top plan view of the superstructure;

Fig. 3 is a plan view of one end of one of the rails of the superstructure showing an approach apron pivotally secured thereto;

Fig. 4 is a side elevation of the part shown in Fig. 3; and

Fig. 5 is a sectional view on the line 5-5, Fig. 3.

At the present time, hydraulic or pneumatic lifts are in use for servicing motor vehicles,

the same being provided with a superstructure of a form suitable to support and elevate a motor vehicle when the ram of the lift is elevated. The present invention refers generally to this type of device, and more specifically to the superstructure and to the ram and the attachment thereto of the superstructure.

Referring now more particularly to the drawings in which similar characters of reference designate similar parts in the several views, in Figs. 1 and 2 there is shown a superstructure, indicated generally at A, mounted on the end of a ram B of an hydraulic lift of any preferred construction, which includes a fixed casing cylinder C embedded in the earth. In the instance shown in the drawings, the ram B is hollow and is guided in cylinder C by the depending flange 2 of a guide casting, indicated generally at 4, which flange is arranged interiorly of the cylinder C and adjacent the upper end thereof. The guide casting 4 includes an upper end 6 which is offset with respect to the flange 2 and which has an annular attaching flange 8 adjacent the flange 2 by which the casting is connected to the cylinder C through the medium of bolts 10 extending through said flange and through an angle ring 12 permanently secured to the cylinder C by being welded thereto, as shown at 14. If desired, a gasket 15 is introduced between the flange 8 and the angle 12, as clearly shown in Fig. 1. As before mentioned, the casting 4 includes the offset portion 6 and this defines a recess within which packing 16 is received, and the upper end of the offset portion 6 is marginally flanged, as at 18, which flange 18 receives attaching bolts 20 which extend through the horizontal portion of a packing gland 22 for an obvious purpose.

Secured within the upper end of the ram B, at a little distance from the upper edge thereof, is a head 24 welded, as at 25, to the interior of the ram; the head 24 thus closing the upper end of the ram, as will be apparent.

Permanently secured to the upper end of the ram is a superstructure support comprising an attaching plate 26 of greater size than the circumference of the ram, which plate

is permanently secured to a plate support 28 in the form of an angle ring by being annularly welded to said ring, as shown at 30. As clearly shown in Fig. 1, the horizontal leg 32 of the angle ring 28 is arranged above the end of the ram and is permanently secured to the ram by being welded to the upper edge thereof, as shown at 34, and the vertical leg 36 of the angle ring is annularly welded to the ram, as shown at 38. By the construction just described, there has been provided a strong and durable superstructure support permanently secured to the ram B, said support directly taking the stresses and strains 15 which otherwise would be transmitted directly to the ram.

Detachably secured to the superstructure support just described is the vehicle supporting superstructure A, which comprises, in the main, a head consisting of a single plate 42 of substantially rectangular form having parallel side edges 44, which may be flanged if desired, as shown at 46, for reinforcing purposes. The ends 48 of the plate have rails 50 secured thereto by rivets 52; the particular description of the rails appearing hereinafter.

Initially the head 42 is a single plate, as before mentioned, and said head comprises a single pressing, the plate being pressed to the form shown clearly in Figs. 1 and 2, thereby providing a central embossment 54 defining a center bearing 56 (see Fig. 1) which in form is adapted to fit over the plate 26 and to be detachably secured thereto by suitable fasteners, such as the bolts 58. Obviously, the center bearing may assume, in outline, any desired form; for example, it may be circular, rectangular or octagon shape depending upon the contour of the plate 26.

40 The central embossment 54 includes the oppositely extending portions 59 which taper downwardly in height from the center bearing 56 toward the ends of the plate 42 and fade into said plate 42 adjacent the inner edge of the base or web of the rails 50, and the sides 60 of said embossment 52 converge toward the ends of the plate. In other words, the embossment comprises a central portion forming a center bearing and gradually diminishing portions extending oppositely therefrom and terminating inside of the ends of the plate 42. As before mentioned, the ends of the plate 42 are designed to support the rails 50, and, to reinforce said ends, the plate 45 is provided with depending ribs 62 arranged on each side of the tapering portions 59 of the embossment 54 and extending to the ends of said plate 42. The drawings disclose the ribs 62 as corrugations formed in the plate, but, obviously, within the spirit and scope of the present invention, the plate may be provided with independent reinforcing members if desired. As clearly shown in Fig. 2, the ribs 62 extend from the ends of the plate 42 55 partially along the tapering portions 59 of the

embossment 54 and said ribs 62, as shown in Fig. 1, diminish in depth near the inner ends thereof, as shown at 64, and fade into the plate 42 at 66 in Fig. 2. For reinforcing the plate 42, angles 68 are secured to the lower surface of the plate adjacent the inner ends of the ribs 62. It will be apparent that the ribs 62, in addition to reinforcing the plate, also serve to support the superstructure when the ram B is in its lowered position; the ribs 62 being adapted to contact with the earth, as shown clearly in Fig. 1.

As before mentioned, the head 42 supports the spaced rails 50, and now referring to Figs. 1 and 2, it can be seen that the rails 50 are substantially channels having a web 70 and inner and outer chords 72 and 74, respectively, which chords are provided with horizontal flanges 76 and 78, respectively, for reinforcing the rails, as will be obvious. Extending transversely across the head 42 and secured thereto by rivets 80, are angles 82, one leg of each of which is riveted to the chords 72 of the rails, as shown at 84.

In the form of superstructure shown in Fig. 2, the ends of the rails 50 are outwardly flared and downwardly bent to provide approaches to permit the wheels of a motor vehicle to easily pass onto the rails 50; the ends being bent a sufficient distance to rest on the surface of the earth when the ram B is in lowered position.

Figs. 3, 4 and 5 disclose one end of a modified form of rail 50 and which is devoid of the integral approach shown in Fig. 2, but is provided with a pivoted approach, indicated generally at 86, the same comprising generally a channel section 88 adapted to underlie the end of rail 50 and having the chords thereof flanged at 90 to underlie the flanges 76 and 78 of the rail 50. The approach 86 is pivotally secured underneath the rail 50 by spaced bolts 92 extending through the web 70 of rail 50 and through the channel 88 and wear-plate 94; bushings 96 surrounding the bolts to reduce friction. For securing the bolts, fasteners such as nuts 97 may be provided.

The rear end of channel section 88 is offset, as shown at 98, and the offset 98 terminates in a flanged foot 100, defining a shoulder 102 adapted to engage the web of the rail 50 when the ram B is elevated to retain the approach 86 against downward swinging. When the ram is in lowered position, as in Fig. 4, the foot 100 rests on the ground whereby to relieve the pivots or bolts of stress when a vehicle is driven onto the superstructure.

From the above description, it is believed that the construction of the superstructure of the present invention will be fully apparent to those skilled in the art, but it is to be understood that the drawings are for illustrative purposes only and that various changes in the form and proportions of the device may be made within the scope of the appended claims.

without departing from the spirit of the invention.

What is claimed is:

1. A superstructure of the kind described comprising a head formed of a single plate having a center bearing pressed therein, reinforcing elements at the corners of said plate and pressed from the plate in a direction opposite that of the center bearing and defining supporting elements for said head when the superstructure is in its lowermost position, and a vehicle supporting rail secured to each end of the plate.

2. A superstructure of the kind described comprising a head formed of a single plate having an embossment formed therein intermediate the margin thereof, said embossment defining a center bearing and tapering reinforcing portions extending oppositely from the center bearing, a rail secured to each end of the plate and arranged transversely with respect to the longitudinal axis of said embossment, and supporting elements on the lower surface of the plate.

3. A superstructure of the kind described comprising a head formed of a single plate having a rail secured to each end thereof and provided with an embossment the central portion of which defines a center bearing, and spaced reinforcing members at each end of the plate on the lower surface thereof and arranged transversely with respect to the longitudinal axis of the rails, said head being a single pressing.

4. A superstructure of the kind described comprising a pressed metal head having an embossment defining a center bearing and portions extending oppositely therefrom and decreasing in depth and fading into said head, spaced channels secured to the ends of said head and arranged transversely with respect to the longitudinal axis of the embossment, downwardly extending reinforcing members at each corner of the plate with the longitudinal axis of each thereof substantially parallel to the longitudinal axis of the embossment, said reinforcing members fading into the head adjacent the ends of the embossment and defining supporting members for the head, and angles secured to the head and arranged transversely with respect to the longitudinal axis of the embossment.

5. A superstructure of the kind described comprising a pressed metal head having a center bearing pressed therein, a rail secured to each end of said head, and approaches at the ends of said rails.

6. A superstructure of the kind described comprising a pressed metal head having an integral center bearing, a rail secured to each end of said head, and approaches pivotally secured at the ends of said rails.

7. As an article of manufacture, a rail supporting head for vehicle lift superstructures comprising a plate having elongated recesses

formed adjacent the corners thereof to define supporting elements, and a central embossment having a portion thereof defining a center bearing, the head being a single pressed unit.

8. A superstructure of the kind described comprising a head having spaced rails secured to the ends thereof and provided with a central embossment defining a center bearing and downwardly tapering portions extending oppositely from the center bearing and terminating adjacent the rails, and reinforcing members on each side of the embossment extending to the ends of the plate to provide supporting elements for the superstructure when in lowermost position, said head being a single pressed unit.

9. In a superstructure of the kind described, an approach comprising a channel section having one end thereof offset to provide an attaching portion, said offset end terminating in a depending flange.

10. In a superstructure of the kind described, a head, spaced rails secured thereto, a channel section having one end offset pivotally secured to the end of each rail at the offset, and a flange depending from the offset to provide a supporting foot for the channel section.

11. In a superstructure of the kind described, a head, spaced rails secured thereto, and vehicle approaches pivotally secured to the lower surface of the rails and having their rear ends offset and terminating in a flange to define a shoulder for limiting the pivotal movement of the approaches, and supporting feet for the approaches whereby to relieve the pivots of stresses.

12. A superstructure of the kind described comprising a pressed metal head having a center bearing pressed therein and having a rail secured to each end thereof.

In witness whereof we have hereunto set our hands.

JOSEPH L. WOOD.
VICTOR WILLOUGHBY.
